OTTO R. FRITZ, OF TORRINGTON, CONNECTICUT, ASSIGNOR OF ONE-HALF TO VICTOR A. ANDERSON, OF TORRINGTON, CONNECTICUT.

PIPE.

1,366,071.

Specification of Letters Patent. Patented Jan. 18, 1921.

Application filed February 17, 1920. Serial No. 359,255.

To all whom it may concern:

Be it known that I, Otto R. FRITZ, a citizen of the United States, residing at Torrington, county of Litchfield, State of Connecticut, have invented an Improvement in Pipes, of which the following is a specification.

This invention relates to tobacco pipes, and its object is to equip a pipe with a novel and satisfactory cleaner.

The invention consists of the construction and arrangement of parts as now to be described and hereinafter specifically claimed.

In the accompanying drawing forming a part of this specification,

Figure 1 is a perspective view of a pipe equipped with the novel cleaner of the invention, showing the cleaner partly withdrawn from the stem;

Fig. 2 a longitudinal sectional view of the pipe, showing the cleaner in the position which it occupies when the pipe is in use; and

Fig. 3 shows the cleaner removed.

10 denotes the bowl, 11 the shank, and 12 the stem of the pipe. Through the shank and stem is the usual smoke passageway or duct 13. The cleaner consists of a slender flexible rod 14, preferably wire, which extends through the passageway or duct. The rod is provided at one of its ends with a head 15, which is adapted to rest in the bottom of the bowl, preferably at or near the center of said bottom, and its other end is bent into the form of a hook 16 which is adapted to rest in a notch 17 in mouthpiece 18 of the stem. The cleaner is preferably made in one piece, that is, the head is integral with the rod. As shown in Fig. 2, 20 the notch in the mouthpiece is made sufficiently deep so that the hook on the rod will be completely out of the way. The rod, as shown, is of a size which precludes its interference with passage of smoke through the smoke passageway or duct, and the head is of sufficient size to clear the smoke passageway or duct of obstructions when the cleaner is withdrawn from the pipe.

It will be apparent that when the head 30 rests in the bottom of the bowl, the part of the rod which extends into the bowl will necessarily be raised from the bottom of the

bowl. The tobacco is thus kept from packing to prevent free passage of smoke from the bowl into the shank. It will further be apparent that the pressure of the tobacco on the head and on the portion of the rod which extends into the bowl, will hold the cleaner in its proper position when the pipe is in use. The rod may be bent at any point which lies in the shank or stem to cause it to engage the wall of the passageway or duct to assist in holding the cleaner in its proper position, as will be readily understood. While I have shown a straight stem pipe, it will be clear that the cleaner of the present invention can be applied to pipes having curved stems.

Should the smoke passageway or duct become clogged, all that is necessary to be done to clean it out is to withdraw the cleaner. The head will remove the obstructions. The cleaner may be wiped off, if found necessary, and replaced in the pipe. It will be apparent that the cleaner can be withdrawn and replaced while the pipe is lighted.

The making of the cleaner in one piece, the largest part of which will slide in the shank and stem, furnishes a very practical cleaner which is conveniently manipulated.

What I desire to claim is:

1. In combination with a pipe provided with a bowl and having a smoke duct and a notched mouthpiece, a one piece cleaner consisting of a rod bent at one end to form a hook and carrying at its other end a head, said rod adapted to lie in said smoke duct, said hooked end adapted to lie in the notch of said notched mouthpiece, and said head adapted to lie in the bottom of said bowl.

2. In combination with a pipe provided with a bowl and having a smoke duct and a notched mouthpiece, a cleaner consisting of a rod provided at one end with a head and at the other end with a hook, said rod adapted to lie in said smoke duct, said hook adapted to lie in the notch of said notched mouthpiece, and said head adapted to lie in the bottom of said bowl, at or near the center of said bottom.

In testimony whereof I affix my signature.

OTTO R. FRITZ.
